Primary Examiner — Stacia Cadmus

CLAIM

The ornamental design for an automotive wheel, as shown and described.

DESCRIPTION

FIG. 1 is a perspective view of an automotive wheel, showing my new design with optional 1 of 2 center cap designs

FIG. 2 is a front view of FIG. 1

FIG. 3 is a perspective view of an automotive wheel, showing my new design without the optional center cap

FIG. 4 is a front view of FIG. 3

FIG. 5 is a perspective view of 2nd optional center cap design; and,

FIG. 6 is the front view of FIG. 5.

The broken line showing of the rear portion of the wheel is included for the purpose of illustrating environment and forms no part of the claimed design.
